UNITED STATES PATENT OFFICE.

HERMAN H. DOEHLER AND MARCUS STERN, OF BROOKLYN, NEW YORK; SAID STERN
ASSIGNOR TO SAID DOEHLER.

KNIFE.

Application filed July 9, 1923. Serial No. 650,327.

To all whom it may concern:

Be it known that we, HERMAN H. DOEHLER, a citizen of the United States, and MARCUS STERN, a citizen of the United States, 5 both residing in Brooklyn, county of Kings, and State of New York, have invented certain new and useful Improvements in Knives, of which the following is a specification.

10 This invention relates to knives of the type in which the blade folds within the handle and which are conventionally known as pocket knives.

It is an object of this invention to produce a knife of simplified construction, the parts of which can be readily manufactured and assembled at low cost.

Another object of the invention is to produce a knife with a one piece handle which 20 can be made, for example, by die casting.

Another object of the invention is to produce a knife in which the spring is not fastened to the sides of the handle, but is retained in place in the handle without direct 25 fastening by means of lugs on the handle and the knife blade.

Other objects and advantages will appear as the description proceeds.

Referring now to the drawings, which illustrate a preferred embodiment of the invention:

Figure 1 is a disassembled perspective view of the major parts of the knife.

Figure 2 is a part sectional view of the assembled knife.

In the embodiment illustrated, the knife consists of four parts, a handle 1, spring 2, blade 3 and the retaining or pivot pin 4 for holding the blade and spring in place in the 40 handle.

The handle 1 consists of the two sides 5, the back 6 and the end 7, which are all in one piece and formed preferably by die casting.

45 The back 6 is provided with two integral upstanding projections 8 and 9, as illustrated, and the sides 5 are provided with a hole 10 for the pivot pin 4. The hole 10 may be formed in the casting operation or 50 may be formed in any suitable way after the casting is removed from the die.

The spring 2 consists of a straight piece of spring metal which is tapered off at the rear as at 11, and provided with the notch 55 12, the end 13 being suitably shaped to co-

operate with the heel of the blade 3. It will be seen that the spring 2 is of a simple construction which can be easily formed, as for example by a stamping operation.

The blade 3 consists of the ordinary cutting portion 14 and the heel 15 which is cut away at 16 to provide a bearing place for the end 13 of spring 2 when the parts are assembled and the blade open. The hole for the pivot pin is indicated at 17.

In assembling the parts the end 11 of the spring is pushed under the projection 8 of the die cast handle 1, and the spring dropped between the sides 5 where it takes the position illustrated in Fig. 2, with the projection 9 extending into the notch 12. The blade is then inserted between the sides 5 and the pivot pin 4 pushed through the holes 10 and 17 and fastened in place. The projection 9, extending into the notch 12, 75 provides a bearing point or fulcrum; and as the rear of the spring is held under the projection 8 the insertion of the blade forces down the end 13 and forces the back of the spring against the back of the handle as at 80 18 so as to provide the necessary spring pressure of the end 13 against the heel 15 of the blade. The spring is automatically retained in place by the blade, making it unnecessary to rivet or pin the spring between the handles, as in the ordinary pocket knife construction.

It will be seen that we have provided a knife in which all the parts are of simple construction and can be formed at a low 90 cost, and which can be readily assembled to form the complete article by unskilled labor.

In the assembled knife, the spring is almost entirely surrounded by the handle portion, which may be a noncorrosive alloy or 95 be protected by a plating, whereby the spring is protected from perspiration and can be carried in one's pocket without rusting.

Various modifications may be resorted to, without departing from the spirit of the invention or the scope of the appended claims, and parts of the device may be used without others.

What we claim is:

1. A pocket knife including an integral 105 handle, a lug on the handle and an undercut beveled recess, the lug and recess being inclined toward the open end of the handle for pivoting the blade within the handle, in engagement with said spring, a spring with 110

a notch in the back thereof and a beveled end enclosed by the handle and fitting over the lug and under the beveled recess, a blade and pivot pin for holding the blade and spring in place.

2. A pocket knife including a handle comprising integral sides, back and end, a pair of upstanding lugs on the back of the handle sloping toward the open end thereof, a recess between the rear lug and the back, a spring adapted to fit over the front lug and into said recess, a blade and a pivot pin for pivoting the blade within the handle, in engagement with said spring.

3. A pocket knife including a one-piece handle with integral lugs, located intermediate the ends thereof, extending inward from the back and sloping in the direction of the open end of the handle, a spring shorter than the handle, engaging the lower surface of one lug and resting upon the upper surface of the other lug, a blade engag-

ing one end of the spring and a pivot pin for holding the blade and spring in place.

4. A pocket knife including an integral handle, a lug on the handle and an undercut recess, the lug and recess sloping toward the open end of the handle, a spring enclosed by the handle and adapted to fit over the lug and into the recess, a blade engaging the end of the spring and a pivot pin for holding the blade and spring in place.

5. A pocket knife, including a die cast handle, comprising integral sides, back and end, a lug on the back of the handle and an undercut beveled recess, the lug and the recess sloping toward the open end of the handle.

In testimony whereof we have affixed our signatures to this specification.

HERMAN H. DOEHLER.
MARCUS STERN.

Certificate of Correction.

It is hereby certified that in Letters Patent No. 1,476,030, granted December 4, 1923, upon the application of Herman H. Doehler and Marcus Stern, of Brooklyn, New York, said Stern assignor to said Doehler, for an improvement in "Knives," an error appears in the printed specification requiring correction as follows: Page 1, lines 109 and 110, claim 1, strike out the words "for pivoting the blade within the handle, in engagement with said spring"; and that the said Letters Patent should be read with this correction therein that the same may conform to the record of the case in the Patent Office.

Signed and sealed this 8th day of January, A. D., 1924.

[SEAL.]

KARL FENNING,
Acting Commissioner of Patents.
